INCORPORATED, OF NEW YORK, N. Y., A CORPORATION OF NEW YORK

WAVE TRANSMISSION

Application filed November 25, 1924. Serial No. 752,082.

This invention relates to transmission of vibratory or wave motion, especially frequency selective propagation of such motion, and aims to obtain selection between adjacent ranges of frequencies mechanically in a simple manner.

Another object is to obtain mechanical selective propagation of a range of frequencies between substantially equal impedances.

Another object is to control the time of propagation of wave motion between two points, in a simple manner, for instance, in order to obtain a desired delay in the propagation of the wave motion or a desired increase in the time of propagation between the two points.

In the design of mechanical wave filters, it is convenient and practicable to follow the analogy of electric wave filters in the cases of low-pass and band-pass structures. For high-pass filters the mechanical equivalent has been more difficult to secure, requiring the use of a structure having a mass in each shunt arm and no mass in the series arms. In accordance with the invention, there is provided a type of mechanical high-pass filter which depends upon a different principle than the ordinary lumped structure, is very simple and inexpensive in construction and has a relatively high loss in the attenuated band.

In the embodiments of the invention specifically illustrated in the accompanying drawings, mechanical torsional vibrations of a range of frequencies are selectively propagated along a rod or wire of uniform circular cross-section, naturally bent into the form of a circular loop or into the form of a plurality of circular loops constituting a helix.

In the drawings, Fig. 1 is an elevation of a system embodying one form of the invention; Fig. 2 is a curve showing the attenuation frequency characteristic of the mechanical wave filter of Fig. 1; Fig. 3 is a perspective view of a portion of a system embodying a modification of the form of the invention shown in Fig. 1; and Fig. 4 represents the electrical analogue of the mechanical transmission system.

Referring especially to Fig. 1, 4 is a circu-

lar loop of round wire which serves as a high-pass mechanical filter. The wire is subjected to torsional mechanical vibrations by a piezoelectric crystal 5. The torsional mechanical vibrations selectively transmitted by the wire 4 are transmitted from the wire to a piezoelectric crystal 6. The crystals 5 and 6 are mounted on a heavy base 7. The crystal 5 may be a composite Rochelle salt or sodium potassium tartrate crystal such as is described in an article by A. M. Nicolson on the piezoelectric effect in the composite Rochelle salt crystal, published in the Proceedings of the American Institute of Electrical Engineers, November, 1919. The crystal 5 may have the usual girdle electrode 8 for connection to one terminal 9 of a source of electro-motive force variations, and an internal electrode 10 for connection to the other terminal, 11, of the source. The connection between the electrode 10 and the terminal 11 may include the base 7, which may be of metal, for instance brass. The electrode 10 may be a bolt or the like, passing through the crystal and in coincidence with the longitudinal axis of the crystal, and supporting the crystal on the base 7, the crystal being clamped between the base and a plate 12 by means of a nut 13 threaded on the bolt 10. The plate 12 is preferably metallic, and may, if desired, be cemented to the adjacent basal plane of the crystal. The opposite basal plane of the crystal may be cemented to the base 7. The cement employed may be melted and super-cooled Rochelle salt, which will set in a short time, upon the agitation incident to its application to the surfaces to be united. The bolt 10 is rigidly connected to the loop 4 by a connector 14. The internal electrode crystal 5 and the method of mounting the crystal are similar to the crystal and mounting method disclosed and claimed in the applications of A. M. Nicolson, Serial No. 655,800, filed August 6, 1923, and issued as Patent No. 1,562,578, November 24, 1925, and Serial No. 683,643, filed December 31, 1923, and issued as Patent No. 1,574,302, February 23, 1926, both assigned to the assignee of this application.

The crystal 6 is similar to crystal 5 and is

similarly mounted on the base 7 and connected to the loop 4.

In the operation of the system shown in Fig. 1 when electro-motive force variations are impressed across terminals 9 and 11, the crystal 5 is caused to undergo elastic twisting vibrations about its principal or longitudinal axis, and the bolt 10 and connector 14 transmit this vibratory twisting motion to the adjacent end of the loop 4, thus setting that end of the loop into elastic torsional vibration. It has been found that the loop acts as a high-pass mechanical filter. The vibrations of the frequencies lying within its pass range are transmitted to the internal electrode of the crystal 6, setting that electrode and crystal into mechanical torsional vibrations about the longitudinal axis of the crystal. This vibration of the crystal 6 generates electro-motive force variations across terminals 15 and 16 which are connected to the girdle electrode and the internal electrode, respectively, of the crystal.

The propagation constant of the high pass filter constituted by the loop 4 is, for any frequency f ,

$$\Theta = \frac{s}{a} \sqrt{\frac{E}{2\mu}} \left[1 - \left(\frac{f}{f_c} \right)^2 \right] \quad (1)$$

or for a single turn,

$$\Theta_o = \pi \sqrt{\frac{2E}{\mu}} \left[1 - \left(\frac{f}{f_c} \right)^2 \right] \quad (2)$$

where

s = distance along the wire

a = radius of helix

E = Young's modulus of material

μ = coefficient of rigidity

and f_c is the cut-off frequency, which is defined by:

$$f_c = \frac{1}{2\pi a} \sqrt{\frac{E}{2\mu}} \quad (3)$$

where ρ is the density of the material.

Above the cut-off frequency the expression for the propagation constant (for the filter or for a single loop) becomes imaginary, and is the expression for the phase shift (for the filter or for a single loop). The velocity of propagation along the loop or helix, at any frequency f well within the pass range, is equal to $(2\pi f)$ divided by the phase shift at that frequency. Below the cut-off frequency the expression for the propagation constant is real, and is the expression for the attenuation.

The coefficient

$$\pi \sqrt{\frac{2E}{\mu}}$$

in Equation (2) is essentially constant for metals which would ordinarily be used. Its value for various materials is: steel, 7.13; aluminum, 7.23; brass, 7.50; German silver, 65 7.13; phosphor bronze, 7.38; copper, 7.29.

These figures result in an attenuation per turn of about 60 TU, that is, 60 transmission units, for low frequencies remote from the cut-off frequency. (The transmission unit referred to here is the unit discussed in the following articles: "The transmission unit" by R. V. L. Hartley, in Electrical Communication, July, 1924, published by the International Western Electric Company, Incorporated, New York; and "The transmission unit and telephone transmission systems" by W. H. Martin, and "Practical application of the transmission unit", by C. W. Smith, both in The Bell System Technical Journal, July, 1924, published by the American Telephone and Telegraph Company, New York.)

The characteristic impedance of the structure approaches that of a straight wire as the frequency increases. Representing this impedance by Z_0 , we have

$$Z_0 = I_o \sqrt{\frac{\mu\rho}{32}} \sqrt{\frac{E}{\mu\rho}} \quad (4)$$

for a round wire, d being the diameter of the wire. The characteristic impedance remains nearly enough constant for large values of frequency when these large values lie in the transmission range so that it is in practice usually necessary to consider only this one value of this impedance. Representing the diameter of the helix by D , the design formulæ are:

$$D = \frac{1}{\pi f_c} \sqrt{\frac{E}{2\rho}} \quad (5)$$

$$d^4 = \frac{32Z_0}{\pi \sqrt{\mu\rho}} \quad (6)$$

These formulæ together with (2) give all the information required in the design of the filter.

As an example, suppose a high-pass mechanical filter is required to cut off at 3,500 cycles and work between impedances of 2006 mechanical ohms in torsion. (A mechanical ohm is 1 dyne per unit velocity, that is, 1 dyne per cm. per sec.; and in torsion, as here considered, a mechanical ohm is 1 dyne per cm. per second, both the force and the velocity being taken at 1 cm. radius.) Suppose the material of the loop to be of steel and that an attenuation of 100 TU is required for low frequencies.

The constants for steel are approximately

$$\rho = 7.9, E = 2.1 \times 10^{12}, \mu = .81 \times 10^{12}$$

then

$$D = \frac{1}{\pi \cdot 3500} \sqrt{\frac{2.1 \cdot 10^{12}}{2.79}} = 33.2 \text{ cms.} = 13.1''$$

$$d^4 = \frac{32 \cdot 2000 \cdot 10^{-6}}{\sqrt{.81 \cdot 7.9}} = .00807$$

or $d = .30 \text{ cms.} = .118''$

The attenuation of a single loop of steel

wire from Formula (2) is 7.13 napiers or 62 TU for low frequencies. Since 100 TU loss is required, we use two complete turns. The complete filter then consists of two turns of .118" steel wire in a helix 13.1" in diameter. The structure cuts off at 3,500 cycles and has the required 100 TU attenuation at frequencies below about 2,100 cycles.

The fact that the propagation constant for the filter is as defined in Equation (1) above, 10 may be seen from the following considerations:

If b is the angular displacement in the plane of the cross-section of the wire, s the 15 distance along the wire, I_0 the moment of inertia of the section about its axis, μ the coefficient of rigidity and ρ the density of the material, we have, for a round straight wire, (equating the potential reaction and the 20 kinetic reaction, as usual, to obtain the wave propagation equation),

$$\mu I_0 \frac{\partial^2 b}{\partial s^2} = \rho I_0 \frac{\partial^2 b}{\partial t^2} \quad (7)$$

If the wire is naturally bent in the arc of a circle, the term on the left, corresponding to the potential energy factor must be changed, owing to the fact that as the wire is twisted torsionally about its longitudinal axis, half 25 of the material at every cross section is put into the condition of tension and half into the condition of compression, the direction of these tensions and compressions being perpendicular to the cross sectional plane, i. e. 30 longitudinal, the dividing line between tension and compression, for small twists, being approximately the sectional diameter which is colinear with the radius of curvature. The 35 restoring force in this case is a function of b alone, rather than of its derivatives.

Letting I_1 be the moment of inertia of a cross-section of the wire about its diameter; a , the radius of the circle in which the wire is naturally bent; and E , Young's modulus 45 for the material, the potential energy due to compression and extension of the material is

$$\frac{1}{2} EI_1 \left(\frac{b}{a} \right)^2.$$

Differentiating this with respect to b to find the restoring force gives

$$\frac{EI_1 b}{a^2}.$$

Equation (7) then becomes

$$\mu I_0 \frac{\partial^2 b}{\partial s^2} - \frac{EI_1 b}{a^2} = \rho I_0 \frac{\partial^2 b}{\partial t^2} \quad (8)$$

This is equivalent to the equation given by 50 Love on page 432 of "The Mathematical Theory of Elasticity" (published by The Cambridge University Press, Cambridge, England) in a treatment of the torsional vibration of a circular ring. Since in the case

of a circular cross-section $I_1 = 1/2 I_0$, and furthermore, since b is a harmonic function of the time, Equation (8) may be written:

$$\frac{\partial^2 b}{\partial s^2} = \left(\frac{E}{2a^2 \mu} - \frac{\omega^2 \rho}{\mu} \right) b \quad (9)$$

where $\omega = 2\pi f$.

The solution of (9) consists of the sum of two exponential terms, one being the original wave and the other the reflected wave. As 75 we are interested only in the propagation constant, the second term is neglected, the solution in this case being:

$$b = Be^{-\theta}, \quad (10) \quad 80$$

where B is the value of b when $s=0$, and

$$\theta = s \sqrt{\frac{E}{2a^2 \mu} - \frac{\omega^2 \rho}{\mu}} \quad (11)$$

Equation (11) is readily reduced to the form 85 of Equation (1).

The effects described by the foregoing equations may be explained in physical terms as follows: In a straight cylindrical rod upon which a torsional vibratory force is impressed the vibratory motion is opposed by the inertia reaction of the particle masses and by the torsional elasticity of the rod. The mass reaction of the particles tends to absorb some 90 of the impressed force, while the elasticity serves to transmit the force from particles in one cross-sectional layer to those in the next. The uniform rod is thus similar to a system of "line", or "series", masses coupled in tandem 95 by springs, forming "coupling", or "shunt", elasticities, but due to the homogeneous structure of the line the individual sections are infinitesimally small. The terms "series" and "shunt", adapted from the terminology 100 of electrical circuits, aptly describe the mechanical reactions with respect to their effects upon the transmitted motion. Series reactions, or restraints, do not diminish the velocity of the motion, but tend to absorb some 105 of the impressed force, whereas shunt reactions tend to absorb some of the velocity while transmitting the force without diminution. 110

When the uniform rod is curved longitudinally, as by bending in the arc of a circle, each cross-sectional element of the rod is deformed into a wedge shaped disc. A twisting movement propagated along the rod tends to rotate the elemental discs about their centers, 115 and in so doing additional restraining forces are called into play. As the narrow edge of the disc is moved out of its original position, the material there is stretched and the displacement is resisted by a longitudinal tensile 120 force. At the wide edge of the elemental disc the rotational displacement is opposed by a corresponding compressional force. That 125 these forces are series restraints tending to oppose the transmission of the impressed 130

force, may be seen from the following considerations: Let it be assumed that the material of the rod is infinitely resistant to compression or extension, it is then obvious that the elemental discs cannot be rotated out of their original positions, and consequently no motion can be transmitted. The line therefore behaves as though the individual mass particles were restrained by infinitely great series elasticities. On the other hand, if the resistance to compression and extension is zero the transmission of torsional vibrations is affected in no way whatever by the curvature of the line, that is, the series elastic restraint is zero.

At low frequencies of vibration the series elastic reaction predominates over the series mass reactions and corresponds to a chain of series and shunt elasticities, both distributed uniformly along the length. Such a structure is effective to attenuate vibratory waves.

Fig. 4 illustrates an electrical transmission line analogous to the mechanical line of this invention. To represent the uniformly distributed character of the impedance elements of the mechanical line, the equivalent electrical line is assumed composed of an infinite number of sections each representing an infinitesimally small portion of the line. Consider the section between the dotted lines AA' and BB'. The series inductance δL_1 , corresponds to the mass of an elemental section of the mechanical line, the shunt capacity, δC_2 , corresponds inversely to the torsional elastance of the elemental section, and the series capacity δC_1 corresponds inversely to the tensional or compressional elastance of the section due to the bending of the line along its longitudinal axis. If L_1 denotes the series inductance per unit length of the electrical line, C_1 the series capacity per unit length, and C_2 the shunt capacity per unit length, then the values for the elemental section are as follows:

$$\delta L_1 = L_1 \delta x;$$

$$\delta C_2 = C_2 \delta x;$$

$$\frac{1}{\delta C_1} = \frac{1}{C_1} \delta x;$$

Where δx represents the length of the line corresponding to the section. The change of potential from A to B is equal to the sum of the back E. M. F.'s in the inductance δL_1 , and the capacity δC_1 . By well known relationships this may be expressed as

$$-\delta v = \delta L_1 \frac{d^2 q}{dt^2} + \frac{i}{\delta C_1} q \quad (12)$$

where q , denotes the electrical displacement in the line at AA', i. e., the quantity of electricity in coulombs traversing the line at AA', v , the voltage across the line at AA', and $-\delta v$ represents the increment of potential in

the section. The charge in the shunt capacity δC_2 is $-\delta q = v C_2 \delta x$, from which

$$-\frac{\delta^2 q}{\delta x^2} = C_2 \frac{\delta v}{\delta x} \quad (13)$$

combining Equations 12 and 13 gives

$$\frac{1}{C_2} \frac{\delta^2 q}{\delta x^2} = L_1 \frac{\delta^2 q}{\delta t^2} + \frac{1}{C_1} q$$

or

$$\frac{1}{C_2} \frac{\delta^2 q}{\delta x^2} - \frac{q}{C_1} = L_1 \frac{\delta^2 q}{\delta t^2}. \quad (14)$$

The range of free transmission may be determined by considering the smooth line as the limiting case of the iterative line shown in the figure as the sections become infinitesimally small. In general, this particular type of structure is a band pass filter having a lower cut-off frequency, f_1 , and an upper cut-off, f_2 , which are expressed by:

$$f_1 = \frac{1}{2\pi} \sqrt{\frac{1}{L_1 \delta x \cdot \frac{C_1}{\delta x}}} = \frac{1}{2\pi} \sqrt{\frac{1}{L_1 C_1}} \quad (15)$$

and

$$f_2 = \frac{1}{2\pi} \sqrt{\frac{\frac{C_2 \delta x + 4C_1}{\delta x}}{L_1 \delta x \cdot \frac{C_1}{\delta x} \cdot C_2 \delta x}} = \frac{1}{2\pi} \sqrt{\frac{C_2 \delta x + \frac{4C_1}{\delta x}}{L_1 C_1 C_2 \delta x}} \quad (16)$$

The lower cut-off frequency, f_1 , by Equation (19), is constant, independent of the length δx , represented by the section. The upper cut-off frequency, f_2 , however, becomes higher as the length δx is decreased; and when δx is zero, as in a smooth line, f_2 is infinite, the structure then being effectively a high-pass filter.

The electrical analogue of the mechanical system is not easy to visualize for the reason that no electrical structure having uniformly distributed series capacity is known. Such a structure, if it could be realized, however, would be governed by Equation (14).

Equation (14) expressing the law of action and reaction in the electrical line, is seen to be of the same form as Equation (8). Electrical displacement q corresponds to the mechanical displacement b ; the quantity μI_0 in Equation (8) corresponds to

$$\frac{1}{C_2}$$

in Equation (14), and may therefore be termed a shunt elastance; the quantity

$$\frac{EI_1}{a^2}$$

corresponds to

$$\frac{1}{C_1}$$

and therefore represents a series elastance; and the quantity μI_0 representing the effec-

tive mass of the line corresponds to the series inductance L_1 . By analogy, Equation (8) expresses the action and reaction in a curved rod or wire in the form of the invention.

5 The cut-off frequency in the electrical line may also be found directly from the solution of Equation (14). If the electrical displacement be assumed a harmonic function of time, i. e., $q = q_0 \sin \omega t$, where q_0 is the maximum 10 displacement and $\omega = 2\pi$ times frequency,

$$\frac{\delta^2 q}{\delta t^2} = -\omega^2 q \quad (17)$$

Substituting (17) in (14):

$$15 \quad \frac{1}{C_2} \frac{\delta^2 q}{\delta x^2} - \frac{q}{C_1} = -L_1 \omega^2 q \quad (18)$$

which can be written,

$$20 \quad \frac{\delta^2 q}{\delta x^2} = \left(\frac{C_2}{C_1} - C_2 L_1 \omega^2 \right) q \quad (19)$$

This equation is of the same form as Equation (9), and if solved in the same manner gives $q = K e^{-P}$ where the propagation constant 25 P is given by

$$P = x \sqrt{\frac{C_2}{C_1} - \omega^2 L_1 C_2} \quad (20)$$

30 The quantity on the right of Equation (20) changes from a real to an imaginary value at the frequency

$$f_1 = \frac{1}{2\pi} \sqrt{\frac{1}{L_1 C_1}}$$

35 which therefore marks the transmission and attenuation ranges.

The theoretical attenuation frequency characteristic of the filter described above is 40 shown in Fig. 2, and agrees with the attenuation frequency characteristic as determined experimentally. The ordinates of the curve in Fig. 2 are attenuation units, each attenuation unit being approximately 8.7 of the TU 45 referred to above.

Fig. 3 illustrates a system employing two loops 20 and 21 similar to the loop 4 of Fig. 1, and constituting a helix having double the attenuation produced by a single loop. Not 50 only the attenuation for the frequencies outside the pass range, but also the time of propagation for the frequencies of the pass range, is directly proportional to the number of loops employed, and this increase in time of propagation is of importance where it is desired to 55 employ the filter as a delay path or means for increasing the time of propagation between translating devices connected to its ends.

In the system of Fig. 3, an electro-mechanical motor element 25, shown as of the type disclosed in H. C. Egerton Patent 1,365,898, January 18, 1921, is employed instead of the piezo-electric motor element 5 of the system of Fig. 1. Any suitable type of motor element and generator element may be utilized,

in either Fig. 1 or Fig. 3. Thus, the generator element (not shown) for connection to the right hand end of the helix of Fig. 3, may be, for instance, an electro-mechanical generator similar to the motor 25, or may be a piezo-electric generator such as the generator 6 of Fig. 1. Preferably, the motor and generator should each have its impedance match that of the loop or helix constituting the filter element. The amplitude of vibration at each frequency of the pass range will then be sustained at its initial value throughout the travel of that vibration along the path.

The frequency selective device of this invention, although of general application as a filter or a means for delaying wave propagation, is especially adapted to serve as a mechanical grouping filter in carrier telegraph or telephone systems.

What is claimed is:

1. A circular helix of round wire with means coupled thereto for imparting to said wire torsional vibrations to be transmitted along the wire.

2. In combination, a circular helix of round wire with means coupled thereto for imparting to said wire torsional vibrations to be transmitted along the wire, the material and the diameter of said wire being such that its characteristic impedance, at the frequencies freely transmitted by the wire, substantially equals the value of the impedance presented to said wire by said means at one of said frequencies.

3. A mechanical wave filter, comprising a curved rod of circular cross-section, the radius of curvature of the rod having a pre-computed value dependent upon the elasticity and the density of the material of the rod and a limiting value of a range of frequencies it is desired to transmit without attenuation, said radius of curvature, elasticity, and density having such values that the rod transmits with practically negligible attenuation sinusoidal mechanical vibrations of all frequencies lying on one side of said limiting frequency while substantially attenuating mechanical vibrations of neighboring frequencies lying on the other side of said limiting frequency.

4. In a mechanical wave transmission system, a mechanical high-pass filter comprising a curved bar and means for vibrating said bar torsionally about its longitudinal axis.

5. In a mechanical wave transmission system, a mechanical high-pass filter comprising a curved bar of uniformly distributed constants, the value of Young's modulus of the material, the density and the rate of curvature being proportioned with respect to a predetermined cut-off frequency so that torsional vibrations of all frequencies above said cut-off frequency are freely transmitted through said filter, while torsional vibra-

tions of substantially all frequencies below said cut-off frequency are highly attenuated.

6. As a frequency selective wave transmission means, a mechanical line comprising a solid medium having elasticities both in series and in shunt with respect to the line of propagation of vibrations impressed on said line, said series elasticity being distributed in accordance with a continuous function of the length along the line.

7. As a frequency selective wave transmission means, a mechanical line in accordance with claim 6 in which both series and shunt elasticities are distributed according to continuous functions of the length along the line.

8. As a frequency selective wave transmission means, a mechanical line in accordance with claim 6 in which the series elasticity is distributed uniformly along a substantial portion of the length of the line.

9. As a frequency selective wave transmission device, a mechanical line comprising an elongated solid member constituting a wave transmission path in which the properties of mass and elasticity are distributed according to continuous functions of the length, said elongated member being curved longitudinally whereby torsional vibratory motion therein is opposed by a plurality of elastic restraints of different types.

10. As a frequency selective wave transmission means, a mechanical line comprising an elongated solid member constituting a wave transmission path in which the properties of mass and elasticity are distributed according to continuous functions of the length, said elongated member being curved longitudinally whereby torsional vibratory motion therein is opposed by a series elastic restraint.

11. As a frequency selective wave transmission means, a mechanical line comprising an elongated solid member constituting a wave transmission path in which the properties of mass and elasticity are uniformly distributed throughout a substantial portion of the length, said elongated member being curved longitudinally whereby torsional vibratory motion therein is opposed by a uniformly distributed series elasticity.

12. A selective wave transmission means comprising a mechanical line having elasticities in series and in shunt with respect to the line of wave propagation, said elasticities being distributed according to continuous functions of the length of the line, and being proportioned, together with the mass coefficients of the line, in accordance with the limits of a preassigned range of frequencies, whereby the line is adapted to transmit freely waves of frequencies within said range, and to attenuate waves of frequencies outside said range.

65 13. In a wave transmission system, broad-

band frequency selective means comprising a mechanical line, and means for impressing mechanical vibrations thereon, said line being adapted by its cross-sectional configuration to oppose one kind of elastic restraint on vibratory motion impressed thereon, and by its longitudinal configuration to oppose another kind of elastic restraint to the vibratory motion, and said elastic restraints together with the mass coefficients of the line being proportioned with respect to the limiting frequencies of a preassigned range whereby the line is adapted to transmit vibrations within said range with substantially no attenuation and to attenuate frequencies outside of said range.

70 14. In a wave transmission system, frequency selective means comprising a uniform mechanical line of elastic material, and means for impressing torsional vibrations thereon, said line being curved longitudinally whereby torsional vibratory motion is opposed by a series elastic restraint, and the degree of curvature being proportioned with respect to the torsional elasticity and the mass of the line to provide a desired wave propagation characteristic.

75 15. In a wave transmission system, frequency selective means comprising a uniform mechanical line of elastic material, and means for impressing torsional vibrations thereon, said line being curved longitudinally with uniform curvature whereby torsional vibratory motion in the line is opposed by series elasticity, the degree of curvature, together with the mass and the torsional elasticity of the line being proportioned in accordance with a preassigned frequency, whereby the line is adapted to transmit freely vibrations of frequencies above the preassigned value and to attenuate vibrations of lower frequencies.

80 In witness whereof, I hereunto subscribe my name this 18th day of November A. D., 1924.

EDWARD L. NORTON.
